UNITED STATES PATENT OFFICE.

ERIK J. BERGE, OF BAYATI, CUBA.

GRATE.

1,378,086.

Specification of Letters Patent. Patented May 17, 1921.

Application filed March 13, 1918. Serial No. 222,228.

To all whom it may concern:

Be it known that I, ERIK J. BERGE, a citizen of Sweden, residing at Bayati, in the Island of Cuba, have invented certain new 5 and useful Improvements in Grates, of which the following is a specification.

This invention relates to improvements in grates and more particularly to furnace grates. Its main object is to provide a 10 furnace grate so constructed as to admit a predetermined amount of air to the fire bed. A further object is to provide a novel form of grate that is simple in construction and operation and that is adapted to economize 15 in the use of fuel. With the foregoing and other objects in view the invention consists in the combination and arrangement of parts to be hereinafter fully described in this specification, pointed out in the appended 20 claims and illustrated in the accompanying drawings which form a part of said specification and in which—

Figure 1 is a side elevation of my improved grate partly in section.

25 Fig. 2 is a top plan view, partly in section and partly broken away to afford a better illustration, taken on line 2—2 of Fig. 1.

Figs. 3 and 4 are fragmentary views illustrating the construction of the grate bars.

30 Fig. 5 is a plan view of the grate with the grate bars eliminated.

Like reference characters denote corresponding parts throughout.

The reference numeral 1 denotes the fire 35 box which is provided with the longitudinally extending rails 2 whereon the wheels 3 run that support the carriage 4 that carries the adjustable frame 5 which is composed of a plurality of levers pivoted together in lazy-tong fashion so that said frame 5 may be extended or contracted. The said frame at its forward end is connected by double links 6 to guard bars 7^a, 7^b of the box 1. Said frame 5 is also engaged 40 at its front end by a rack 7 which extends through an opening in the front end of the said box 1. A segment 8 fast upon a rod 9, journaled in bearings 10 carried by the carriage 4, is in mesh with the said rack 7 and a lever 11 fast upon said rod 9 extends 45 through the opening 12 in the front end of the fire box and serves to rotate said rod 9 and so actuate said segment.

Grate bars 13 spaced apart are formed 55 with longitudinal slots 14 in which the castings 15 are disposed that are formed with

longitudinal slots 16 through which the bolts 17 extend that also pass through pivotal points 18 of frame 5 whereby said grate bars are secured to said frame; said bolts 60 17 being provided with the nuts 19. Each bar 13 is formed with a rearwardly extending flange 20 so that space between any two bars may be entirely or partly bridged to regulate the flow of air between said 65 bars. In Fig. 1 the bars 13 are shown close together. To widen the space between them the lever 11 is manually raised thereby narrowing the width and extending the length of the frame 5, since said frame is connected 70 to the said links 6 and is operably connected to said rack 7 in mesh with the segment 8 controlled by said lever. The fuel lies directly upon the grate bars and is prevented from falling off the same at each end 75 of the carriage 4 by the guard ribs 21. The said carriage 4 is mounted upon wheels to facilitate its complete removal from the fire box when desired for purpose of repair, cleaning purposes or the like.

80 What is claimed is:—

1. In a furnace construction, a fire box, a carriage removably disposed within said fire box, grate bars, a frame secured to said grate bars and composed of parts pivotally secured together and relatively adjustable to vary the length of the frame, thereby varying the distance between the grate bars, and manually operable means mounted on said carriage and engaging said frame for adjusting the latter.

2. In a furnace construction, a fire box, rails extending longitudinally of said fire box, a wheeled carriage removably disposed upon said rails, spaced slotted grate bars, a frame secured to the slotted portions of said grate bars and composed of parts pivotally secured together and relatively adjustable to vary the length of the frame, thereby varying the distance between the grate bars, and manually operable means mounted on said carriage and engaging said frame for adjusting the latter.

3. In a furnace construction, a fire box, a carriage removably disposed in said fire box, spaced slotted grate bars, a frame secured to the slotted portions of said grate bars and composed of parts pivotally secured together and relatively adjustable to vary the length of the frame, thereby varying the distance between the grate bars, a rack carried by said frame, and a toothed segment car-

ried by said carriage and in mesh with said rack.

4. In a furnace construction, a fire box, a carriage removably disposed within said fire box, spaced grate bars formed with rearwardly extending flanges to bridge the spaces between the bars, a frame secured to the slotted portions of said grate bars and composed of parts pivotally secured together and relatively adjustable to vary the 10 length of the frame, thereby varying the

distance between the grate bars, and manually operable means mounted on said carriage and engaging said frame for adjusting the latter.

In testimony that I claim the foregoing as my own I have hereto affixed my signature in the presence of two subscribing witnesses.

ERIK J. BERGE.
